UNITED STATES PATENT OFFICE.

CHARLES A. ROTTHOUSE, OF BRANDYWINE HUNDRED, DELAWARE, ASSIGNOR OF
ONE-HALF TO EDWARD G. COOK, OF WILMINGTON, DELAWARE.

CLOTHES HANGER.

Application filed August 28, 1925. Serial No. 53,180.

This invention relates to clothes hangers and has for its object the provision of means whereby a large number of articles of wearing apparel may be stored within a small space and arranged in a convenient manner so that any one garment or article may be removed when desired. The invention seeks to provide means for the stated purpose which will firmly support the garments whether they are arranged close together for storage or are more or less separated to permit removal of any desired garment or to permit inspection without actual removal. The invention is illustrated in the accompanying drawings and consists in certain novel features which will be hereinafter first fully described and then more particularly pointed out in the appended claims.

In the drawings:

Fig. 1 is a view, partly in section and partly in elevation, showing the device arranged within a closet to support garments in compact form and economize space;

Fig. 2 is a similar view showing the device extended to permit inspection or removal of the garments;

Fig. 3 is a plan view of the device in its extended position;

Fig. 4 is a detail perspective view of the supporting end of the device;

Fig. 5 is a detail horizontal section on the line 5—5 of Fig. 1, and

Fig. 6 is an enlarged detail elevation of a portion of the device in its folded position.

In the drawings, the reference numeral 1 indicates the back wall of a closet or other compartment. In carrying out the invention, I rigidly secure to the said back wall a base or supporting bracket 2 which, as shown most clearly in Figs. 3 and 4, is a channeled member having its flanges extending vertically and projecting from the wall 1 or other fixed support. Fitted through the side flanges of this base or main supporting bracket adjacent the upper ends thereof is a pivot rod 3, and a similar rod 4 is inserted through slots 5 extending vertically in the lower portions of the flanges. Pivots engaged with the ends of the upper rod 3 at the outer sides of the main supporting bracket are the upper ends of links 6 which extend from the pivot rod in parallel relation and disposed between the said links 6 are other parallel links 7 which have their lower ends piv-

totally engaged with the ends of the rod 4 at the outer sides of the supporting bracket. The links 6 and 7 are pivotally connected midway their ends by a pivot rod 8 and through the upper ends of the links 7 is fitted a pivot rod 9. Upon the said pivot rod 9 is pivotally mounted the upper end of a short link 10 and the upper end of a long link 11 which is approximately twice the length of the link 10. To the lower ends of the links 6 are pivoted a short link 12 and a long link 13, the pivots 14 by which these links are connected to the links 6, however, being merely short pins extending through the ends of the links instead of a rod bridging the space between them. The links 10 and 11 converge from the rod 9 and the links 12 and 13 likewise converge from their respective pivots, all these links meeting at a point substantially midway the ends of the links 11 and 13 and being pivotally connected by a pin or rivet 15, as shown. The links 11 and 13 are slightly bent beyond the pivot 15 and extend therefrom parallel with a plane passing longitudinally of the structure midway the ends of the several rods 3, 4, 8 and 9. The outer ends of the links 11 and 13 are thus brought into substantially the central longitudinal plane of the device, while the arrangement of the links shown and described provides a wide substantial support for the inner end portion of the device so that it will firmly support the garments suspended thereon and will be held against undue lateral vibration or other movement. To the ends of the links 11 and 13, other links 16 and 17 are pivotally attached and other links, corresponding to the links 16 and 17, may be provided in any desired number and pivotally connected at their ends and at their centers so as to produce a lazy tongs arrangement of any desired length. The outermost link 18 of the series of links is extended past its pivotal connection 19 with the adjacent end link 20, and knobs 21 or the like are secured to the extremity of said link 18 to provide a handle whereby the device may be conveniently manipulated. In the upper opposed edges of the lower ends of the several links are formed upwardly opening notches 22 which, as shown in Figs. 1 and 2, are adapted to mate when the device is collapsed or folded so that they will encircle the suspending hook 23 of a garment support en-

gaged therein. Between the lower ends of adjacent pivotally connected links are disposed washers 24 which have grooved peripheries, as shown most clearly in Fig. 5, whereby they are adapted to firmly support the hooks 25 of garment supporting devices. The garment supporting members may be of any well-known type and are illustrated as each consisting of a hook, such as 23 or 10 25, having its lower end swiveled in a bar 26 which is of arcuate formation whereby it may be engaged within the shoulder portion of a garment and support the same in such manner as to tend to preserve the shape and 15 fitting qualities thereof.

When garments are to be suspended on the device, the handle 21 is drawn outwardly to approximately the position shown in Fig. 2 so that the lazy tongs will be extended. 20 The hooks of the garment supports may then be engaged in any of the notches 22 and will be suspended therefrom to be firmly supported against accidental or premature release while at the same time any desired 25 garment may be easily removed when necessary. Garments may also be supported in the device by having the hook members of the clothes supports engaged over the washers 24, as shown in Fig. 2. When the device 30 is extended, the garments will be separated to a greater or less extent and any one garment may be inspected and turned as may be needed without disturbing any other garment. When the device is folded into the 35 closet or against any other fixed support, the mating notches of adjacent links will completely encircle the hooks suspended in the notches, as shown in Fig. 1, so that dropping of the garment supports from the links 40 will be prevented. As the device folds, the garment supports suspended from the washers 24 will readily swing into position between other garments inasmuch as the bar 26 of the support is swiveled upon the hook 45 and may easily turn thereon, as will be understood upon reference to Fig. 1.

It is to be noted that, when the device is extended, the links which are pivoted together at their lower ends will assume a divergent relation and sufficient space will be developed between them to permit the hook of the garment holder to be easily engaged in any desired notch. Moreover, the hook to be suspended from a washer 24 will be 50 guided into engagement with the washer by the opposed faces of the adjacent links and the washers will serve to hold the lower ends of the links separated sufficiently to permit the hook to easily slip into engagement with the washer. Moreover, when the device is 55 collapsed, the adjacent links will tend to fit over the opposed portions of the hooks which rest on the washers and will thereby, to an appreciable degree, serve to lock the hooks 60 against accidental release. The pairs of 65

links 6, 7, 10, 11, 12 and 13 provide a relatively wide support for the device and at the same time permit the garment carrying links to readily fold close to the main supporting bracket 2, as shown in Fig. 1. When the 70 device is extended, the garments will be sufficiently separated to permit a circulation of air around all the garments, and this feature of the device permits the condition of the clothes to be examined whenever desired 75 so that the ravages of moths may be counteracted and any dust which may have settled upon the clothes may be removed. The device may be secured in any closet and will 80 obviously accommodate a large number of garments in a smaller space than has been heretofore possible.

Having thus described the invention, I claim:

1. A clothes hanger comprising a base to 85 be secured to a fixed support, a pair of links pivotally attached to the upper end of said base at opposite sides thereof, a second pair of links having sliding engagement with the said base at opposite sides thereof, a pivotal 90 connection between the pairs of links at the centers thereof, other links pivotally attached to the outer ends of the links of the pairs of links, said last-mentioned links converging outwardly and being pivotally connected in a plane substantially midway the 95 sides of said base, certain of the last-mentioned links being extended forwardly beyond the pivotal connection in opposed vertical directions, a series of links pivotally connected to each other and pivotally connected to the forward ends of said extended links, and means upon the lower end portions of all the links to be engaged by a 100 garment support.

2. A clothes hanger comprising a base to 105 be secured to a support, a pair of links pivotally attached to said base and spaced from each other transversely of the base, a second 110 pair of links slidably engaged with said base in spaced relation to each other transversely of the base and in vertical spaced relation to the first links, said pairs of links extending in crossed relation to each other and pivotally connected, other links pivoted to 115 the outer ends of the links constituting the pairs of links and converging outwardly and pivotally connected in a plane substantially midway the links of the pairs of links, certain of the last-mentioned links being 120 extended outwardly beyond the pivotal connection in opposed vertical directions, and a series of pivotally connected links pivotally attached to the outer ends of said extended links, certain of said links being 125 adapted for engagement by garment supports.

In testimony whereof I affix my signature.

CHARLES A. ROTTHOUSE. [L. S.]
